Inventor:

Arthur Lenhart

UNITED STATES PATENT OFFICE.

ARTHUR LENHART, OF PORTLAND, OREGON.

CAR-COUPING.

SPECIFICATION forming part of Letters Patent No. 286,207, dated October 9, 1883.
Application filed October 30, 1882. (Model.)

To all whom it may concern:

Be it known that I, ARTHUR LENHART, a citizen of the United States, residing at Portland, in the county of Multnomah and State 5 of Oregon, have invented a new and useful Car-Coupling, of which the following is a specification.

My invention relates to improvements in car-couplings; and its objects are, first, to secure a perfect and complete coupling that can be used on all rolling-stock of every description, and which will couple itself without human agency when brought together, and, second, can be uncoupled from the top or either 15 side of the train without passing between the cars. I attain these objects by the mechanism illustrated in the accompanying drawings, in which—

Figure 1 is a view of the coupling as constructed, showing the under part or bottom of the car; and Fig. 2 is a sectional view, showing the draw-head cut in the center.

It consists of the draw-head *a*, with the hook *c* on one side and the tongue *d* on the other, 25 and the small semicircular recess *e*, suited for one-half of the pin *f f*, cut out of the center, attached to the draw-bar *b* by means of and so as to turn on a bolt. The draw-heads, coming together, form a double catch, one on 30 either side, and form, by the semicircular recesses meeting in the center, a round hole for the pin *f f*. This pin is the means which fasten the coupling, and by which it is uncoupled. It is halved in two, and each part is fitted in 35 the recess *e*, and held to its place with its face *v* (see Fig. 2) at an oblique angle to the face of the draw-head, by the spring *u*, and so as to be turned till its face becomes parallel and flush with the face of the draw-head. 40 The face of the draw-head runs obliquely to a line at right angles with the central line of the car, sufficiently to slip into its place invariably by the pressure of the connecting cars. The semicircular parts of the pin *f f* in each 45 draw-head are pressed down till they become flush with the face of the draw-head and till they slip into their proper places. Then they spring back to their original oblique angle, forming together, a round pin exactly fitting 50 the opening, and finally fastening the coupling

so that they will never part, no matter from what direction comes the strain.

The couplings are uncoupled by turning the pin till the faces of its parts become parallel with the face of the draw-head, when the connection will be entirely free, there being a smooth surface running clear across the draw-heads, allowing them to part when separated. Each half of the pin *f f* has the small crank *g* underneath the draw-head, and is connected 60 by means of the small crank *h* to the elbow-crank *i*, attached to the draw-bar under the car, which changes the motion, and from thence to the crank *k*, on either side of the car, one of which cranks, on all box-cars, is attached 65 to a rod running to the top of the car, so that they may be uncoupled from the top or either side of the train by the use of the handle *l*, so arranged with jaws as to be readily attached to the crank and to be carried by the train-men.

The means of uncoupling these couplings, being concentrated in a single pin formed by the two halves meeting in the center, allows the coupling to be uncoupled from either car, as 75 the turning of one half turns the other. Therefore a coupling may be uncoupled though one side be broken and disconnected, or be only attached to a link-and-pin draw-bar, as it may be.

The parts claimed as my invention are the draw-head and bar divided in two parts, and connected so as to turn when necessary. The draw-head may also be attached to a link-and-pin draw-bar, if desired, the double catch on 85 either side, with a plane face, serving for a buffer between, and the concentration of the means of coupling and uncoupling in a single pin in the center formed by the two halves meeting, and the connections arranged to enable them to be uncoupled from either side or 90 top of the train.

I claim—

1. The combination, in a car-coupling, of a draw-head, *a*, with a hook, *c*, on one side and 95 a tongue, *d*, on the other, and a semicircular recess, *e*, and pin *f f* in the center, the pin *f* held to its place, with its face at an oblique angle to the face of the draw-head *a*, by the spring *u*, with its connection to the draw-bar 100

b by means of a pin, for the purpose of allowing the draw-head to swing to one side when coupling.

2. In a car-coupling, the combination of the connecting-rods *h* and *j*, and the cranks *i* and *k* with the crank *g* on pin *f*, for the purpose of turning pin *f* till its face becomes flush with face of draw-head, all as substantially set forth.

3. The handle *l*, limited to the use as shown, and in combination with the lever *k*, rod *j*, and bell-crank lever *i*, as substantially set forth.

ARTHUR LENHART.
